UNITED STATES PATENT OFFICE

2,604,769

YARN FEED ASSEMBLY

Eugene St. Pierre, Pawtucket, R. I., assignor to
 Hemphill Company, Central Falls, R. I., a corporation of Massachusetts

Application November 22, 1949, Serial No. 128,693

3 Claims. (Cl. 66—131)

1

This invention relates to a new and useful improvement in yarn feeding devices for circular, independent needle, knitting machines.

One form of the device is shown in the drawing, of which:

Fig. 1 is a plan view;

Fig. 2 is a side elevation;

Fig. 3 is an enlarged partial side elevation;

Fig. 4 is a front elevation corresponding in extent to Fig. 3.

Fig. 5 is a still further restricted partial side elevation illustrating a position assumed by the device; and

Fig. 6 is a similar front elevation.

As shown, the device consists of a body 1 suitably supported on the carrier ring of the machine which is slotted as at 2 which slot is partially closed by cover plates 3 and 4 so that a slide-way is formed within which a slide 5 can move vertically. Affixed to slide 5 or an integral part thereof is yarn lever 6. Projecting laterally from slide 5 is a stud 7 positioned so as to be engageable with an adjustable stop 8 whereby the downward limit of movement of yarn lever or yarn feeding finger 6 is determined. Slide 5 is also provided on its other side with another pin 9 to which is attached one end of a spring 10, the other end of which is held by a bracket 11 so that yarn lever 6 is urged upwardly. Body 1 is also provided with a curved extension 12 which forms the support for a pivot screw 13 upon which is pivoted a member consisting of an upwardly extending arm 14 and a lateral extending arm 15. As best shown in Figs. 1, 4 and 6, arm 14 is bent so that its free end overlies the upper end of slide 5. This end of arm 14 is provided with an adjustable stop 16 overhanging the upper end of slide 5. Arm 15 overlies a lever 17 pivoted to a suitable bracket 18. Lever 17 is provided with a slot 19 along which a pin 20 is able to move. Pin 20 is fixed in one end of another lever 21 pivoted to bracket 18 at 22 and pivotally connected at its other end 23 to a rod 24 which in turn is operatively connected to a pattern drum (not shown) provided with suitable operating cams. The unit consisting of arms 14 and 15 is urged by spring 25 into the position shown in Fig. 2 in which stop 16 overlies the upper end of slide 5 as already explained.

The device above described operates as follows. If end 23 of lever 21 is lowered, the opposite end of lever 17 will also be lowered with the result that yarn lever 6 is pushed down to its lowest position indicated by dotted lines in Fig. 4. At this position, pin 7 will rest upon stop 8. It is

2

to be assumed that this position of yarn lever 6 is lower than the normal yarn feeding position and is to insure that the yarn is low enough to be properly taken by the needles.

If lever 24 is now raised sufficiently, yarn lever 6 will be raised to the full-line position shown in Fig. 4 at which it engages stop 16. This may be assumed to be the normal yarn feeding position. This position may, of course, be varied by adjusting stop 16 so that the feeding position is independent of the exact position of lever 17.

When yarn lever 6 is to be moved out of yarn feeding position, rod 24 is raised still further with the result that the opposite end of lever 17 is also raised. This in turn will raise arm 15 which will swing arm 14 out of its vertical position so that stop 16 will no longer overlie the upper end of slide 5 and slide 5 will be moved to its uppermost, inactive position by spring 10 or as shown in Figs. 5 and 6. A stop 26 (Fig. 2) limits the movement of levers 21 and 17 to that required for this purpose since excessive movement of those levers might swing arm 15 so far that spring 25 would be unable to bring it back. To bring yarn lever 6 back into feeding position, end 23 of lever 21 is lowered which correspondingly lowers the opposite end of lever 17 so that yarn lever 6 is carried to its lowermost position as already described. At the same time, arm 14 is swung back into its vertical position by spring 25 so that it is again in position to limit the upward movement of yarn lever 6 to its yarn feeding position.

It is always desirable that the cams on a pattern drum have a uniform maximum height so that they can be cut from standard cam rings. It sometimes happens that this standard height does not provide sufficient motion for the usual type of operating mechanism to move a device such as a yarn lever through the required distance as would be the case of the device described above. The device of this invention makes such moves possible without undue complication. Also, the device of this invention permits of accurate positioning of the yarn feed at its yarn feeding height irrespective of small amounts of lost motion in the operating mechanism.

I claim:

1. A yarn feed assembly for a circular, independent needle, knitting machine which includes a vertically slideable yarn feeding finger, means operatively associated with said finger for permitting it to move upwardly, a displaceable stop for limiting the upward movement of said finger, said means also constituting means for lowering

said finger to a desired lower position and for displacing said stop so that when said stop is displaced said finger can move to a position higher than that permitted by said stop.

2. A yarn feed assembly according to claim 1 in which said means also serves as a stop to limit the extreme upward movement of said finger.

3. A yarn feeding assembly for a circular, independent needle, knitting machine which includes a reciprocable yarn feeding finger, a movable stop for limiting the movement of said finger in one direction, said stop being movable out of the path of the travel of said yarn finger in said direction to permit said finger to move 15

further in said direction, and means for so moving said stop.

EUGENE ST. PIERRE.
